UNITED STATES PATENT OFFICE.

CHARLES G. KELLY, OF PHILADELPHIA, PENNSYLVANIA.

METAL-CASED PIPE-COVERING.

No. 926,423.

Specification of Letters Patent. Patented June 29, 1909.

Application filed October 9, 1906. Serial No. 338,147.

To all whom it may concern:

Be it known that I, CHARLES G. KELLY, a citizen of the United States, residing in the city and county of Philadelphia, State of Pennsylvania, have invented a new and useful Metal-Cased Pipe-Covering, of which the following is a specification.

In the manufacture of pipe coverings there is considerable difficulty in retaining the parts in place where they are made separate and when applied and considerable inconvenience and additional cost in the preparation of the covering in place.

Those casings which have an exterior surface of cloth or of the material of which the casing itself is chiefly composed are liable to mechanical injury and the subject of joints for separate pipe coverings both longitudinally and transversely united has given considerable trouble.

The purpose of this invention is to provide a pipe casing and covering which shall maintain the shape of the cover in rigid form, shall be readily and quickly separable and attachable, shall itself form a bowl for the material of which the casing is chiefly composed and shall provide reliable fastenings and junctions both for straight pipe lengths and for angles and connections.

Figure 1 represents a perspective view of a cross-connection embodying my invention, the ends being sectioned to show the pipe and covering. Figs. 2 and 3 represent corresponding views of a simple connection and a corner or bend. Fig. 4 represents an elevation partly broken away to show a section of pointed straight pieces of the outer casing without the filling material. Fig. 5 represents a transverse section of the parts of my pipe covering in separated position. Fig. 6 represents a transverse section of my pipe casing and covering in place about a pipe. Figure 7 represents a modified form of joint.

Similar numerals of reference indicate corresponding parts in the figures.

Referring to the drawings, 1 designates a pipe which is in the form shown in Fig. 1, cross-jointed to form connection 2 completing a four-way joint. This is covered by an outer metallic casing formed in two sections 5 and 6 divided preferably approximately in the central plane of the two pipes and containing the filling material 7 which is set within each of the casing parts, using them

as a mold, and is divided at the central plane. One outer casing part is inwardly and rearwardly bent to form a portion 8, bent back again and spaced at 9 returning upon itself and in the direction of the initial extension of the metal 10 to provide a pocket 60 between the parts 8 and 10 to receive an extension 11 from the member 6, said extension 11 being formed at the end of an inward bend 12, whose purpose is to bring the material of the extension 11 in line with the pocket 13 between the extensions 8 and 10 of the portion 5. A similar form of connection is used to form a longitudinal joint in each of the forms which I have illustrated, this joint being the same about the straight, curved 65 and connecting pipes. In the form shown in Fig. 2 the pipe 14 is joined by pipe 15 to make a T or three-way connection. The portions 16 and 17 correspond in general shape to the T just as the portions 5 and 6 75 correspond to the cross-connection of Fig. 1. In Fig. 3 a curved form is shown in which sections 18 and 19 offer the forms and protections for the material therein shown and are arranged to cover any bend or turn in the 80 pipe 20. In all of these forms the parts are retained about the pipe by any suitable connection, preferably a swinging arm 21. Pivot 22 is sufficiently loose to permit this strip 21 to swing about the pipe and into 85 place over button or nut 23 which lies within slot 24.

In Fig. 4 the longitudinal connection which I preferably use is shown. The end of the outer casing 25, is inwardly and rearwardly 90 turned at 25', extends as at 26, is again turned at 27, allowing a space 27' between the part 26 and the return 28 within which the edge 29 is adapted to be passed. While this joint is desirable upon the joining ends 95 of the pipe it is most desirable for the longitudinal joints in that the curvature of the space 13 and corresponding curvature of the edge 11 from the other member make these parts spring into place and cause a more 100 effective joint for all purposes than would be possible with the closeness of fit, permissible between metals which must be stamped to place and parts for which must be interchangeable although made by different dies. 105

Fig. 7 indicates a modified form of longitudinal joint in which the material is extended, as at 30 to the end 31 of the female mem-

ber and the material upon the opposite side of the joint is correspondingly cut away, as at 34.

It will be apparent that my longitudinal and transverse joint may be used with other forms of securing mechanism within the latches 21 and that any desired filling material may be used, the only requirement being that it have sufficient heat insulating properties.

Having thus described my invention, what I claim as new and desire to secure by Letters Patent, is:—

1. In a device of the character described, a casing longitudinally divided in halves and a filling therefor in combination with a longitudinal junction for each edge of said casing, comprising reversely bent edges from one member, forming curved pockets and extensions from the other member fitting into said pockets.

2. In a device of the character described, a metallic casing longitudinally divided in halves, a filling therefor, a pivoted latch retaining the parts in closed position and a longitudinal spring joint between each pair of adjoining edges of the two halves formed by successive reverse bends upon one part to

form a circumferentially curved pocket and a circumferentially curved coöperating edge 30 upon the other of the meeting parts.

3. A casing for pipe joined at an angle, comprising longitudinally divided rigid half covers similar to the joint formed by the pipe, filling material within said covers, 35 pockets formed along the meeting edges of said covers by reverse bending of the covers, and projecting curved edges coöperating with said pockets.

4. A casing for pipe joined at an angle 40 comprising longitudinally divided half covers similar to the joint, coöperating interfitting curved edges and pockets upon the covers and filling material within the halves.

5. A casing for pipe joined at an angle, 45 comprising longitudinally divided half covers conforming to the shape of the joint and provided with curved edges and mating curved projections inset from the surface of the cover respectively, filling material within 50 the halves, and a latch for retaining the covers together.

CHARLES G. KELLY.
